TUBING BLEEDER

Harry L. Laughinghouse, Long Beach, Calif.

Application February 25, 1935, Serial No. 7,950

1 Claim. (Cl. 137—111)

This invention relates to a tubing bleeder by means of which the tubing in a well can be drained prior to the removal of said tubing from the well.

An object of my invention is to provide a tubing bleeder which normally is sealed to prevent bleeding of the tubing, but which can be broken or shattered by means of a tool being dropped into the tubing, thereby providing orifices which are open to the tubing and will thus bleed the same.

Another object is to provide a tubing bleeder which can not be accidentally opened during the normal pumping operation of the well and which will remain closed at all times until a tool is dropped into the tubing to shatter a transverse glass tube.

Still another object is to provide a tubing bleeder which is simple in construction and inexpensive to manufacture, and which can be quickly and easily replaced to seal the tubing after it has been shattered, in order to bleed said tubing.

Other objects, advantages and features of invention may appear from the accompanying drawing, the subjoined detailed description, and the appended claim.

In the drawing

Figure 1 is a longitudinal sectional view of the tubing bleeder in assembled position in a well.

Figure 2 is a sectional view taken on line 2—2 of Fig. 1.

Referring more particularly to the drawing, the numeral 1 indicates the outer stationary barrel of a pump—of usual and well known construction. This barrel is mounted on a shoe 2. In the drawing, the working barrel or plunger—as well as the standing valve—are not shown, for the reason that these parts, together with the sucker rods, are removed from the well before my bleeder is released.

A bleeder sub 3 screws into the lower end of the shoe 2 and a cage 4 screws into the lower end of the sub 3. A ball check valve 5 is mounted in the cage 4 and the ball rests upon the usual seat 6.

If desired, a gas anchor (not shown) may be

mounted below the cage 4, and for this purpose, I provide a coupling 7 which screws into the lower end of the cage 4. The gas anchor then screws onto the coupling 7 in the usual and well known manner.

My bleeder is mounted in the sub 3 and consists of a glass tube 8. This glass tube extends transversely thru the sub 3, as shown in Fig. 2. To prevent leakage around the tube 8, I provide packing 9 and 10 around each end of the tube 8, and annular nuts 11 and 12 screw into the sub against the packing 9, 10, respectively thereby holding the tube 8 in position and also preventing leakage around the tubing.

When it is desired to bleed the tubing which extends above the pump 1, a heavy bar is dropped into the tubing from the surface. This bar falls to the bottom and strikes the glass tube 8; this glass tube shatters, thus leaving two open passages one on each side of the sub 3 thru which the fluid in the tubing can pass. In breaking the glass tube 8, the portion within the wall of the sub 3 normally remains, thus providing a wall in the opening which wall cannot be readily cut by the rush of fluid, which—in the case of an oil well—contains considerable sand. The glass tube 8 is preferably the usual gage glass which is always available around an oil well, or the like. After this tube has been shattered, the parts still within the wall of the sub can be easily removed by simply withdrawing the threaded annular nuts 11 and 12.

The check valve 5 prevents the oil from flowing back into the well under normal operation of the pump and the tube can be bled of its fluid only by shattering the tube 8.

Having described my invention, I claim:

A tubing bleeder comprising a sub adapted and arranged to be mounted below a pump, said sub having oppositely disposed aligned holes in the side thereof, a frangible tube extending transversely thru said sub and thru said holes, packing in the holes around the tube, and packing nuts threaded into the holes and arranged around the tube.

HARRY L. LAUGHINGHOUSE.
